UNITED STATES PATENT OFFICE.

FRIEDRICH EBERT, OF STUTTGART, GERMANY, ASSIGNOR TO THE FIRM OF UNION
SPECIAL-MASCHINENFABRIK G. M. B. H., OF STUTTGART, GERMANY.

INDICATING MECHANISM.

1,128,960.

Specification of Letters Patent.

Patented Feb. 16, 1915.

Application filed October 27, 1910. Serial No. 589,306.

To all whom it may concern:

Be it known that I, FRIEDRICH EBERT, engineer, a citizen of the German Empire, residing at Stuttgart, in the Kingdom of 5 Wurttemberg, Empire of Germany, have invented certain new and useful Improvements in and Relating to Indicating Mechanism; and I do hereby declare the following to be a full, clear, and exact description of 10 the invention, such as will enable others skilled in the art to which it appertains to make and use the same.

This invention relates to an improved indicating mechanism for money changing 15 and issuing machines. In the apparatus of this kind hitherto employed stepped frames rocking on their axes are used, the separate steps of which according to their position as regards height determine the amount of the 20 rocking movement and therewith also the figure value, and are moved by spring action against the key bar which is at that time adjusted. These said stepped frames in consequence of their weight necessitate a 25 very strong spring for operating them, which imparts to them by reason of their considerable weight, a correspondingly great impetus, whereby by repeatedly striking the key bars they of course damage the places 30 encountered and thereby alter the position of the working parts of the apparatus, which of course has an unfavorable influence on the working of the entire apparatus.

35 This invention has for its object to remove this disadvantage and this is attained by the key bars themselves being so formed in place of the ordinary stepped frames cut in a cylinder casing, that their ends lie step- 40 wise side by side and they are locked in their lowest position by an easily rocking bar. The entire construction of the apparatus is substantially simplified and cheapened by this arrangement.

45 The invention will now be more particularly described in connection with some forms of construction shown as an example in the accompanying drawings.

50 Figures 1 to 3 show a form of construction of the improved machine partially in section in side view, plan view and in another position of the parts; while Fig. 4 is a side view partially in section of another form of construction. Figs. 5, 6, 7 and 8 55 represent detail views illustrating the differ-

ent positions of the parts in the coöperative movements of the slide jaw 23 and the nose 28.

In this invention the key bars 1 (Figs. 1 to 3) are prolonged at one end in such a 60 way that they lie side by side like steps. The prolongations 2 of the key bars 1 have projections 3 against which when the bar 1 is depressed a rocking contact bar 4 rests. A bar 4 is provided for each series of keys, 65 that is to say both for the tens as well as for the units of the mark and pfennig divisions (where the machine is arranged for German coinage). All the bars 4 turn loosely on a spindle 5, and are connected by levers 6 70 with segments 7. The segments 7 are in direct connection by means of toothed wheels 8 and 9 with the shaft 10 for moving the inspection wheel 11. Each of the key bars 1 also has a prolongation 12, which on the depression of the keys takes with it a drawbar 13 which engages on one arm 14 of a pawl 15 and thereby lifts this out of a notch 16 in the 75 rocking segment lever. The levers 6 and with them also the bars 4 are acted on by a 80 spring 17.

On the operating shaft 18 a lever 19 is arranged which carries a rack bar 20 which is pivotally mounted at 21 and is brought by the intermediary of a spring 22 by a slide 85 jaw 23 into and out of engagement with a toothed segment 24 mounted on the shaft 5. The toothed segment 24 and also a recoil frame 25 and crossbar 38 of the segment lever 6 are in their usual position pressed by 90 a spring 26 against the stop 27.

The rack bar 20 is provided at its free end with a laterally extending nose 28 which acts in conjunction with the sliding jaw 23 which holds the bar out of engagement with 95 the segment 24.

In the form of construction shown in Fig. 4, the key bars 1 are provided at both ends with prolongations 3, both sets of which lie stepwise side by side. In this arrangement, which is intended for the case in which several figures are provided on each key, a similar arrangement like the one hereinbefore described is adopted at 100 the other end of the bars, levers 30 resting on a shaft 29, which levers carry a stop bar 31 corresponding to the bar 4, while the bars 1 themselves have a prolongation 32 which acts on a drawbar 33 and pawl 34 105 which engages behind a projection or heel 110

35 of the lever 30. In this case the contact bars 4 and 31 are connected with one another by a bar 36, so that when the keys are depressed they are compulsorily moved against 5 one another.

The improved machine is operated as follows:—On the depression of a key and key bar 1, a segment lever 6, which is loosely mounted on the shaft 5, is released, the nose 10 of the key bar prolongation 12 commencing to take the drawbar 13 with it to about half the extent of the movement of the bar 1 and thereby lifting the pawl 15 out of its notch 16, whereupon the spring 17 comes into action, which draws the lever 6 so far that the bar 4 bears against the projection 3 of the key which is at the movement depressed, whereupon the bar 1 is locked in this position by the bar 4. Now at the same time 15 the segment 7 is turned and this transmits its movement through the toothed wheels 8 and 9 to the inspection wheels 11, and the proportions of transfer are so selected that the movement of the bar 4 transmitted to 20 the number wheels 11 always exactly corresponds to the desired figure value, and the indicated number visible in the ordinary inspection hole is thereby simultaneously transmitted by the shaft 10 to the indicating 25 mechanism. When the amount in question has been indicated in the manner hereinbefore described, the hand lever 37 is moved to the left, so that the shaft 18 rotates with it, the lever 19 thereby draws the rackbar 30 20 back, while the nose 28 slips away over the projection 23 without the rackbar coming into engagement with the segment 24. By this means the point at which the spring 25 acts is displaced to the left, so that this 25 spring in the next succeeding movement to the right of the lever 37 brings the rack bar 20 into engagement with the segment 24, and, as the nose 28 slips through under the projection 23, this causes a rotation of the 30 segment 24 and the shaft 5 together with the crossbar 38 firmly connected with it, which then rests against the segment 7, and moves this segment together with the contact bar 4 back into the initial position. 35 In this movement the spring 26 is stretched, which as soon as the rack bar 20 is brought by the spring 22 out of engagement with the segment 24 draws back the lever 25 and therewith the crossbar 38 into the initial 40 position, that is to say until it rests against its stop 27.

Now as the initially depressed key is also again moved into the initial position by its spring after the release of the bar 1 by the bar 4, the operation can be repeated in the same way.

As shown in Fig. 5, the spindle 5, the lever 25, the cross-bar 38, the rack 20 and the nose 28 are in normal position. In 45 operating the lever 37 in the direction of

the arrow, the nose 28 will pass over the slide jaw 23.

In Fig. 6, when the lever 37, as well as the rack 20 with the nose 28 has reached its extreme left hand position, the spring 22 70 has changed its active position with respect to the pivot point of the rack bar, and the nose 28 is about starting to snap off from the slide jaw 23.

In Fig. 7, the nose has passed off from 75 the slide jaw 23 and has become coupled with a segmental gear 24, the latter being connected with the spindle 5, and when the lever 37 returns in the direction of the arrow, the parts coupled are moved simultaneously.

In Fig. 8 the lever 37 has reached its normal position and the nose 28 is about snapping off from the slide jaw 23 shortly before the uncoupling of the segmental gear 85 24. Therefore, the rack 20 can not yet release the segmental gear 25 which is under the pressure of a spring 26 and allow it to swing back with spindle 5, lever 25, and cross bar 38 to normal position. 90

In the arrangement shown in Figs. 1-3, one key series of 18 keys (Fig. 2) suffices for the operation of each of the mark and pfennig divisions, as in this case the keys from 10-90 each indicate one number which 95 appears at the tens place, while the keys from 1-9 indicate the figures at the units place. The form of construction in Fig. 4 on the other hand is intended for apparatus in which the separate keys carry several 100 numbers, in which case 99 keys are necessary for each of the mark and pfennig divisions.

I declare that what I claim is:—

1. An indicating device for money-changing and coin-issuing machines, comprising 105 keys arranged side by side and stepwise at both ends, indicating wheels, means for oscillating said wheels, and means controlled by said stepwise arrangement at each end of 110 the keys for limiting the movement of its respective wheel, whereby one key may indicate one or more numbers.

2. An indicating device for money-changing and coin-issuing machines, comprising 115 stepwise arranged key bars side by side and having projections thereon, an indicating wheel, a double-armed rocking lever for operating said indicating wheel, and a contact bar carried by the lever for engaging the projections on the stepwise key bars for limiting the movement of said lever. 120

3. An indicating device for money-changing and coin-issuing machines, comprising 125 stepwise arranged key bars side by side and having projections thereon, an indicating wheel, a double-armed rocking lever, a toothed segment carried by one end of the lever for operating said indicating wheel, and a contact bar carried by the opposite 130

end of the lever for engaging the projections on the stepwise key bars for limiting the movement of said lever.

4. An indicating device for money-changing and coin-issuing machines, comprising stepwise arranged key bars side by side, an indicating wheel, a double-armed rocking lever, a toothed segment carried by one end of said lever for operating said indicating wheel, means for locking the toothed segment, an upwardly extending arm carried by the key bar, means operated by said arm for releasing the locking means, and a contact bar carried by the opposite end of the lever for engaging the stepwise key bar for limiting the movement of said lever.

5. An indicating device for money-changing and coin-issuing machines, comprising stepwise arranged key bars side by side, an indicating wheel, a double-armed rocking lever, means carried by one end of the lever for operating the indicating wheel, a contact bar carried by the opposite end of the double lever for engaging the stepwise key bar for limiting the movement of said lever, and means for stopping said lever at the moment at which the bar encounters the step of said key bar.

6. An indicating device for money-changing and coin-issuing machines, comprising stepwise arranged key bars, side by side, an indicating wheel, a double-armed rocking lever, means carried by one end of the lever for operating the indicating wheel, the opposite end of the lever engaging the stepwise key bar for limiting the movement of said lever, means for stopping said lever at the moment the lever encounters the step of said key bar, and means for returning

the lever to its initial position against the action of its spring.

7. An indicating device for money-changing and coin-issuing machines, comprising stepwise arranged key bars, side by side, an indicating wheel, a double-armed rocking lever, a spring operating on said lever, means carried by one end of the lever for operating the indicating wheel, the opposite end of the lever engaging the stepwise key bar for limiting the movement of said lever, means for stopping said lever at the moment the lever encounters the step of said key bar, means for operating the lever, and means operated by the lever-operating mechanism for uncoupling the lever at the end of its forward stroke, whereby the lever is returned by the action of the spring to its initial position.

8. An indicating device for money-changing and coin-issuing machines, comprising stepwise arranged key bars side by side and having projections thereon, an indicating wheel, a spring-operated lever released by the depression of a key, a toothed segment connecting the lever to the indicating wheel to move the same, a contact bar carried by the lever, engaging a projection and thus limiting the movement of the lever, means for uncoupling the lever at the end of its forward stroke, and a spring for returning the lever to its initial position.

In testimony whereof I affix my signature, in presence of two witnesses.
